LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed June 17, 1922. Serial No. 568,897.

This invention relates to internal combustion engines and to the valves of such engines, and more particularly to the cooling of the exhaust valves of high speed, heavy duty engines such as are used in the propulsion of aircraft. It has for its principal object to provide an improved method for cooling such valves, and improved apparatus of the character designated which shall maintain the valves of such engines relatively cool under all conditions of engine operation.

The high temperatures to which the exhaust valves of internal combustion engines are subjected is well known, particularly in engines of the aeromotive type in which valves have been known to operate at temperatures approaching white heat. Such temperatures prohibit the use of high compression in the engine cylinders, or the use of lean fuel mixtures therein, and seriously curtail the life of the valves, as is well understood in the art to which my invention relates.

The method herein disclosed effects a cooling of the valves by dissipating in a stream of cooling water the heat absorbed by a relatively small part of the cooling water which is brought into heat exchange relation with the highly heated portions of the valves.

The invention may be practiced by means of apparatus shown in the accompanying drawing and described hereinafter, the specific constructional characteristics of which may be varied widely and are herein set forth merely by way of illustration. Referring to the drawing, Fig. 1 is a view, partially in section and partially in elevation, of a portion of an engine cylinder provided with a valve constructed in accordance with my invention, and Fig. 2 is a diagrammatic plan view, illustrating the application of my invention to an internal combustion engine, a portion of the valve actuating mechanism being removed for the sake of clarity.

The specific details of construction of a power plant to which the invention may be applied, have not been illustrated, since they are well known in the art and form, per se, no part of the present invention, but in a general way there is illustrated a power de-

veloping cylinder 10 of such a power plant, having a head 11 in which is located a poppet valve 12.

The valve 12 is formed with a hollow head portion 13 and a hollow stem portion 14 integral therewith. The head portion 13 is provided with an end wall 15 which may be integral with the head portion, or firmly secured thereto in any well known manner, as by welding. The exterior of the head member is provided with a beveled seating surface 16, adapted to cooperate with a suitable valve seat 17, formed on the cylinder head 11.

The valve stem 14 is mounted to reciprocate in suitable guides 18, and is provided with suitable springs 19 by means of which the valve is urged against its seat 17. The valve is adapted to be actuated against the action of the springs 19 by suitable mechanism operated in synchronism with the engine cycle. As shown, this mechanism comprises a rocker lever 21, suitably pivoted at 22 and operated by a push rod 23, which is driven in timed relation to the engine cycle. It is to be understood, however, that any well known valve actuating mechanism may be used.

The upper portion of the valve stem 14 is provided with a suitable connection affording communication with the interior of the hollow valve head 13. As shown, this connection is a T fitting 24, suitably secured to the valve 14, as by a clamping cap 26, so that its stem portion 27 is in axial alignment with the valve stem 14. The arms which compose the head of the T fitting are preferably formed as nipples 28, adapted for connection to flexible conduits 29 and 31, conveniently composed of rubber tubing.

The conduits 29 and 31 are connected by suitable nipples to manifolds 32 and 33 respectively, which are conveniently arranged along the heads of a bank of the cylinders 11, as best shown in Fig. 2. The manifold 32, which is adapted to supply cooling water to the valves, is connected by a supply pipe 34 to the cold water side of the engine cooling system, preferably on the pressure side of a circulating pump 36, com-

monly used in the art to ensure a circulation of cooling water in the system. The manifold 33, which is adapted to remove the overflow of cooling water from the valves, is 5 connected by a pipe 37 to the hot water side of the engine cooling system, preferably near the inlet to the usual cooling device or radiator 39.

It is apparent from the foregoing description that a portion of the water in the engine cooling system is by-passed through the pipe 34, the manifold 32, and the conduit 29, to the connection 24, flowing through and across a portion of the hollow 15 valve stem 14, and overflowing through the conduit 31, the manifold 33, and the pipe 37 to return to the cooling system.

A small portion of the cooling water passing through the connection 24 passes through 20 the hollow stem 14 and enters the hollow head 13, which is highly heated by the combustion of gases in the engine cylinder 10. This portion of the water is vaporized by 25 the heated valve head 13, the vapor rising through the hollow stem and carrying with it a certain amount of heat. On contact with the stream of cooling water flowing through the connection 24, this vapor is condensed in, and the condensate carried away 30 with the stream of cooling water, thus dissipating its heat therein.

It is apparent that this invention provides a method of cooling the valves of internal combustion engines in which an excess of cooling water is supplied to the 35 valve, a small portion only of which is brought into heat exchanging relation with the valve head, the remainder being permitted to flow away through the valve stem.

40 The vapor generated in the heated head is discharged through the valve stem, where it is condensed and the absorbed heat dissipated in the stream of cooling water passing through the valve stem.

45 Although the invention has been described in but one form, it will be obvious to those skilled in the art that it is not so limited, but is susceptible of various other changes and modifications, without departing from 50 the spirit thereof, and it is to be understood, therefore, that only such limitations shall be placed thereupon as are imposed by the prior art or as are specifically set forth in the appended claims.

55 I claim—

1. In an internal combustion engine having a cylinder provided with a valve seat, a hollow poppet valve cooperating with the seat and having a hollow stem, means for 60 causing a stream of water to traverse a cool portion of the stem to make available a supply of water to the interior of the valve proper, and means to remove the overflow of water from the stem.

65 2. In combination with an internal com-

bustion engine provided with a water cooling system, a hollow poppet valve having a hollow stem, and means to by-pass a part of the water from the cooling system through a cool portion of the stem to ensure 70 a supply of water to the hollow valve and to condense vapor generated therein.

3. In combination with an internal combustion engine provided with a water cooling system, a hollow poppet valve, means 75 including a flexible conduit to lead water under pressure from the cooling system to and across the stem of said valve, and means including a flexible conduit to return water overflowing from the stem to the cool- 80 ing system.

4. In combination, a valve including a hollow head and a stem having a passage communicating with the inside of said head and a conduit connected to said valve stem, 85 said conduit having a continuous duct intersecting said passage for supplying a stream of cooling fluid to said valve.

5. In combination with an internal combustion engine including a plurality of 90 cylinders and valves to be cooled, a source of cooling fluid, a supply conduit and a return conduit connecting said source to said cylinders, whereby a circulation of cooling fluid is produced, and a path in shunt to said 95 supply and return conduits, said path including a supply manifold having parallel branches associated with individual valves and a return manifold having similar 100 branches associated with individual valves, whereby a quantity of said cooling fluid is by-passed through said branches for cooling said valves.

In testimony whereof I affix my signature.
